UNITED STATES PATENT OFFICE.

WALTER P. MURPHY, OF CHICAGO, ILLINOIS.

UNCOUPLING-LEVER.

1,099,993.

Specification of Letters Patent. Patented June 16, 1914.

Application filed February 13, 1912. Serial No. 677,402.

To all whom it may concern:

Be it known that I, WALTER P. MURPHY, a citizen of the United States, residing at Chicago, in the county of Cook and State 5 of Illinois, have invented certain new and useful Improvements in Uncoupling-Levers, of which the following is a specification.

The object of my invention is to provide an uncoupling lever or release rigging 10 wherein the joint between the hand lever and the pin lifting lever is such that it will permit the hand lever to return to normal position after operating the pin lever without moving the pin lifting lever from its 15 abnormal position; and with this and minor objects, my invention consists of the parts and combination of parts as will be herein-after pointed out.

This application contains matter divided 20 out of my applications, Serial No. 519,471 and Serial No. 602,664.

In the drawing, Figure 1 is an end view of a car, parts being broken away with my improved rigging in position; Fig. 2 is a 25 similar view showing the locking pin up and the locking pin lever in abnormal position; Fig. 3 is a top plan view of Fig. 1; Fig. 4 is an enlarged detail view of the joint between the hand lever and the pin 30 lever; Fig. 5 is a top plan view of another embodiment of my invention partly in section; and Fig. 6 is a side elevation of the same.

The reference numeral 1 indicates a car 35 body of any approved construction, 2 the end sill and 3 brackets of a standard make secured to the end sill.

4 is the coupler head secured to the car.

The hand lever 5 is journaled in the 40 brackets 3 and retained therein by means of the cotter pins 6. The outer end of the lever 5 is deflected downwardly inside the corner plate 7 as at 8 to a point below the under face of the end sill and thence outwardly toward the side of the car as at 9, thus forming a crank handle which may be operated either by the hand or foot of the trainmen to revolve the lever 5. The inner end of the lever 5 is bent outwardly 45 to form a crank 10 which has a closed eye 11 on its outer end.

The locking pin lever 12 is of a diameter adapting its inner portion to pass through the locking pin 13, the inner end of the 55 lever being bent to form a hook 14 to prevent the lever from becoming accidentally

disengaged from the locking pin. The outer end of the locking pin lever 12 is bent to form an eye 15 which is adapted to engage the eye 11 of the hand lever as 60 more clearly shown in Fig. 4. In the embodiment shown in Figs. 1, 2, 3 and 4, I bend the lever 12 downward as at 16, thus forming a seat in which one side of the eye 11 is positioned when the lever is in the 65 position shown in Fig. 1; however, the lever 12 need not necessarily be provided with this downward bend 16 but may be straight from its eye 15 to its inner end as shown in Figs. 5 and 6.

In Figs. 5 and 6, the crank 10^a of the hand lever is provided with an elongated eye formed by a return bend 17, the end of which is bent inward as at 18 against one side of the crank 10^a, as shown in Fig. 5. 70 The locking pin lever 12^a is provided with a hook 14^a on its inner end and with an eye 11^a on its outer end, there being lugs or bosses 19 on each side of the eye 11^a which constitute an extended seat 20, which 75 is convex on its side walls and concave on its bottom wall. The convex walls permit sidewise movements of the lever 12^a but at the same time prevent the lever from moving too far toward the end sill. 80

In use, the locking pin 13 is raised from locked position by operating the crank on the outer end of the lever 5, thereby elevating the crank 10 which carries with it the locking pin lever to the position shown 90 in Fig. 2. Under the safety laws, the crank 9 must be returned to a point below the under face of the end sill. As will be seen the eye of the lifting pin lever engages the eye of the crank of the hand lever, which 95 will permit the crank to return to normal position after operating the pin lever without moving the pin lifting lever from its abnormal position as shown in Fig. 2.

I claim:

1. A release rigging including a crank having a return bend at its inner end, the end of said bend being bent in against the crank to form a horizontally disposed eye, and a pin lifting lever having a vertically 105 disposed eye at its outer end to engage said return bend and overlie the crank thereby forming a joint which will permit the crank to return to its normal position after operating the pin lever without moving the pin 110 lifting lever from its abnormal position.

2. A release rigging including an elong-

gated crank having a closed eye at its inner end, and a lifting pin lever having an eye at its outer end to engage the eye of the crank, lugs extending from each side of the lower portion of the eye of the pin to form an extended bearing for the lever in the elongated eye of the crank; the joint between the two eyes permitting the crank to return to normal position after operating the pin lever without moving the pin lever from its abnormal position.

3. A release rigging including a pin lifting lever having a closed eye at its outer end, lugs extending from each side of the lower portion of said eye and having convex inner walls constituting an extended

bearing, and a crank having a return bend at its inner end, the end of which is bent in against one side of the crank to form an elongated eye on the side of the crank, 20 the eye of the pin lever engaging the return bend to form therewith a joint which will permit the crank to return to normal position without moving the pin lifting lever from its abnormal position.

25 In testimony whereof I affix my signature in presence of two witnesses.

WALTER P. MURPHY.
